Letters Patent No. 83,575, dated October 27, 1868.

IMPROVEMENT IN THE PREPARATION OF ROOFING-FABRICS.

The Schedule referred to in these Letters Patent and making part of the same.

To all whom it may concern:

Be it known that I, J A Y J. W I G G I N, of Syracuse, in the county of Onondaga, in the State of New York, have invented a new and useful Machine for the Manufacture of Composition-Roofing for houses, boats, cars, &c.; and I do hereby declare that the following is a full, clear, and exact description of the construction and operation of the same, reference being had to the annexed drawing, making part of this specification, in which—

Figure 1 is a longitudinal sectional view,
Figure 2 is a top view, and

Figure 3 is a transverse sectional view of the same.

The nature of my invention consists in the peculiar mechanism I employ for the coating of paper or cloth fabrics with any composition for roofing-purposes.

In the drawings, A is the metal frame, in which the pressure-rollers B B B are fastened.

A' is the roller for the paper or cloth fabric.

A", the handle by which the frame A and rollers B B B are put in motion.

B B B, the pressure-rollers.

C, the box or trough for the composition.

D, the fabric rolled around A'.

a', the standards for holding the handles A".

b, the nuts by which the pressure-rollers are secured to the frame A.

b' b' b", the holes for the introduction of steam through the nuts into the rollers, and

b" b" b", the holes for the introduction of hot water into the rollers.

c, the metal plates or rails on the inside of the box or trough, for B B B to roll upon.

I construct my sand-box or bed C of wood, or other suitable materials, from fifty to one hundred feet long, two feet wide, and four inches deep, the side pieces higher than the end pieces, by about one-half inch. Then, on the inner upper edge of each of said pieces, I let into, and fasten to them, iron bars or rails c c, of suitable form and strength to sustain the heavy rollers B B B, fig. 1. The box is then filled, to within about two inches of the top of the side pieces, with clay, which is packed closely while in a damp condition, and then allowed to dry, and become hard, as a bedding for the sand, which is then spread evenly upon it, after being heated hot, until it reaches within a half inch of the upper edges of the sides of the box, and then the box will be ready for use.

The three iron pressure-rollers B B B are to be made about three feet long, ten inches in diameter, hollow for the admission of hot water or steam into them, and to weigh about two hundred pounds each.

The frame A A is made of two iron bars, of proper dimensions to hold the pressure-rollers by the nuts b b.

Two upright bars or standards, a a, are fastened upon the bars A A, to support the felt-roller A, which is let into them, so as to revolve freely, and pay out

the felt, paper, or cloth, when rolled upon it for that purpose.

Two other bars, a', are fastened upon the bars A A, behind the felt-roller, and at such an angle that the handles A, fitted into their ends, may be conveniently held by an operator walking behind the frame A A.

The pressure-rollers should be placed in the frame at the distance of about six inches from each other.

Holes should be made, b' b' b", in and through the nuts b b b, into the interior of the pressure-rollers, for the introduction of steam, when it is desired to heat them with steam, and holes b" b" b" may be made in the rollers themselves, when it is desired to use hot water for the same purpose.

The nuts b b are to be screwed into the ends of the rollers, and the outer ends thereof made square, or in any other suitable form for being inserted or removed by a wrench.

When hot water is used to heat the pressure-rollers, it may be introduced by any suitable means, and when steam is to be used, the boiler, or other receptacle, containing it, may be moved along by the side of the rollers upon a carriage, mounted upon wheels, or in any other suitable manner, and connected with the rollers by pipes.

The operation of the mechanism so constructed, may be described substantially thus:

Hot sand having been spread upon the clay bed to such a depth as to leave space between its surface and the upper edges of the metallic plates or rails c, sufficient for a layer of the composition of the desired thickness, the free end of the piece of felting D, (which should be several inches wider than the space between the metal plates or rails c,) is placed over the box, and upon the composition as it is poured over the sand, and the frame A is moved forward by the operator, by the handle A", when the roller A' will pay out the felting as required.

By operating this machine in this way, the article of manufacture before mentioned is completed for use as fast as the rollers are moved over the box. When an excess of composition is poured into the box, such excess runs over the sides of it, and may be saved for future use.

My machine has been proved, by experiments, to be superior to all others known or used heretofore, in several respects. Where the bedding for composition has been wholly of sand, it has been found to yield and be pushed forward before the front roller; but in my bed, the layer of sand being thin upon the firm bed of clay, the latter material, by its peculiar nature, will not allow the sand to slip over it; and again, the sand, by being hot, unites more readily and thoroughly with the composition, and co-operates with the hot rollers, forming with and upon the composition, that stony crust which enables my roofing to resist both fire and water more successfully than that made by another machine.

The rollers B B B, if cold, would, to some extent, cool the composition, and would prevent that thorough union and cementation of the sand and composition which are secured by heat, as well as by the weight of the rollers themselves.

In the use of other machines with but one roller, it has been necessary to make two or three successive operations upon the same piece of roofing before its formation would be complete, involving much time and expense, which are avoided by the use of my machine.

In the use of my machine, with its three rollers, one operation is superior in effect to three successive operations with a machine with a single roller. For in using a machine of the latter kind, the composition and sand would have time to cool, to some extent, between each operation and the succeeding one, and the result would not be so good as that of the one operation of my machine, the three rollers of which follow each other in such quick succession that no appreciable loss of heat would take place between the pressure of the first roller and that of the second and third.

The heating, and keeping hot during the operation, the pressure-rollers, are productive of the most valuable results to the manufactured article.

Claims.

What I claim, and desire to secure by Letters Patent, is—

1. The box or bed C, constructed as and for the purpose described.
2. The three rollers B B B, constructed and arranged substantially as and for the purpose described.
3. The rolling-apparatus, composed of the three rollers B B B, the frame A A, and the parts contained in the same, constructed and arranged substantially as and for the purposes set forth and described.
4. The heating and keeping hot the rollers B B B, by the introduction into them of either hot water or steam, substantially in the manner set forth.
5. The process, herein described, of coating felt, paper, and other roofing-fabrics, the same consisting in the use of heated rollers acting over a clay bed, or its equivalents, constructed substantially as described.
